DESIGN FOR A STORE SIGN

Benjamin Shapiro and Isadore M. Kay, St. Louis,
Mo., assignors to The Berland Shoe Stores, Inc.,
St. Louis, Mo., a corporation of Missouri

Application January 28, 1935, Serial No. 55,118

Term of patent 7 years

To all whom it may concern:

Be it known that we, Benjamin Shapiro and Isadore M. Kay, citizens of the United States, residing at the city of St. Louis, State of Missouri, have jointly invented a new, original, and ornamental Design for a Store Sign, of which the following is a specification, reference being made to the accompanying drawing, forming a part thereof, in which Figure 1 is a perspective view and Figure 2 is a plan view of a store sign embodying our design.

We claim—

The ornamental design for a store sign, substantially as shown.

ISADORE M. KAY.
BENJAMIN SHAPIRO.
